DESIGN FOR A COVER FOR A PHONOGRAPH-CASE.

56,035.

Specification for Design.

Patented Aug. 10, 1920.

Application filed September 6, 1919. Serial No. 322,202. Term of patent 7 years.

To all whom it may concern:

Be it known that I, FERDINAND L. STEGER, a citizen of the United States, and a resident of Steger, in the county of Will and the State of Illinois, have invented a new, original and ornamental Design for a Cover for a Phonograph-Case, of which the following is a specification, reference being had to the accompanying drawings, forming a part thereof.

The drawing is a perspective view of the cover for a phonograph case embodying this design.

I claim:

The ornamental design for a cover for a phonograph case substantially as shown. In testimony whereof, I have hereunto set my hand at Steger, Illinois, this 3rd day of September, 1919.
